UNITED STATES PATENT OFFICE.

JOHN D. ROBERTSON, OF DE RIDDER, LOUISIANA.

OIL-STOVE.

1,146,817.

Specification of Letters Patent. Patented July 20, 1915.

Application filed July 7, 1914. Serial No. 849,510.

To all whom it may concern:

Be it known that I, JOHN D. ROBERTSON, a citizen of the United States, residing at De Ridder, in the parish of Beauregard and State of Louisiana, have invented new and useful Improvements in Oil-Stoves, of which the following is a specification.

This invention relates to improvements in oil stoves and burners therefor and consists in the construction, combination and arrangement of devices hereinafter described and claimed.

One object of the invention is to improve the construction of an oil stove whereby the oil supply tank for the burners is arranged below the bottom shelf in the bottom of the stove and out of the way.

Another object is to provide improved means for supporting the burners and bracing the same and for also supporting the globes or chimneys used on the burners.

In the accompanying drawings, Figure 1 is an elevation of an oil stove constructed in accordance with my invention and provided with my improved burners. Fig. 2 is a vertical central sectional view of the main burner and also a detail sectional view of the bottom shelf and oil supply tank. Fig. 3 is a vertical sectional view of the main burner on a plane at right angles to that of Fig. 2. Fig. 4 is a detail vertical central sectional view of one of the subsidiary burners. Fig. 5 is a view of a fragmentary part of the burner.

The stove 1 is here shown as provided with a portable oven 2, with a top 3, a bottom shelf 4, and with supporting legs 5 by means of which the bottom shelf is spaced above the floor.

In accordance with my invention I provide an oil supply tank 6 for the burners. This tank is of oblong rectangular form, is horizontally arranged, and is arranged under the bottom shelf 4, with one end projecting beyond one end of the stove, and the said oil supply tank is secured in place under the shelf by means of strap hangers 7. At the outer end of the tank 6 is a gage 8 to indicate the quantity of oil in the tank under all conditions. An oil supply pipe 9 is also provided, which has a funnel 10 at its upper end and is also provided at its upper end with a screw cap 11. A pump for supplying compressed air to the tank, above the body of oil therein, is indicated at 12. This air compressing and supply pump is vertically arranged, the lower end of its

cylinder is connected as at 13 to the tank and the upper end of the cylinder is held by a brace 14. A piston or plunger rod of 60 the pump is indicated at 15 provided at its upper end with a cross handle 16. This pump may be of any suitable construction and is employed for compressing air in the tank to bear on the body of oil and subject the latter to such pressure as to cause the oil to be readily fed through the oil supply pipe to the burners.

The stove is here shown as provided with a main centrally located burner 17 and with 70 a pair of subsidiary burners 18 which are on opposite sides of and are suitably spaced from the main burner.

Each burner comprises a base 19 and a hollow head 20 which has a vertical central 75 induction and mixing tube 21, an inner wall 22 and an outer wall 23. The base is circular and has an annular wall 24 at its outer edge, on its upper side. At the center of the base is a circular opening around which 80 is a depending wall 25. The outer wall 23 of the head may be formed with the base. Said wall 23 is spaced from and arranged concentric with the wall 24, and has a central opening around which is a tubular portion 26 which is between the depending wall 25 of the base and the lower end of the mixing tube 21. A web 27 connects the upper end of the mixing tube with the upper side of the inner wall 22 of the head. A cap 28 90 is screwed on the upper side of the outer wall 23 of the head and spaced above the web 27. Thereby a chamber is formed between the members of the head, which chamber extends around the head and also between the web and cap, the upper end of the mixing tube discharging into the center of said chamber. The outer wall 23 of each 95 head is foraminous, being provided with perforations as at 29.

A band 30 extends around and is secured to the base of each burner at a point a suitable distance below the upper side of its wall 24. Each band is secured to the upper ends of the braces 31, the lower ends of which are 100 secured on the bottom shelf 4 of the stove. These braces are suitably spaced apart. Two of them are used for supporting the main burner and four of such braces are used for supporting each subsidiary burner. 110 A generating cup 32, to which alcohol may be supplied is arranged a suitable distance below the main burner and is also secured to and between its braces 31 and supported and

secured between the oil supply pipes 33 of the main burner.

The main burner is here shown as provided with a pair of oil supply pipes, the lower ends of which extend down into and nearly to the bottom of the tank 6 and are provided with gauze or other suitable strain-
ers 34. Each oil supply pipe is also pro-
vided with a suitable regulating valve 35
10 and with coils 36-37. The coils 36 of the two oil supply pipes are arranged with their convolutions interposed so that the convolutions of said coils alternate. These coils are in superposed relation and are arranged on
15 the inner side of the inner wall 22 of the main burner head. The coils 37 of the oil supply pipes are also interrelated and their ends arranged under and near the outer edge of the base of the main burner. Oil sup-
20 plied to the coils through the pipes 33 is vaporized in the coils when the main burner is in operation and the vapor escapes from the coils through the downturned ends 38 of said oil pipes 33, said downturned ends
25 converging downwardly and being connected to a vapor supply pipe 39 which leads to the subsidiary burners and has each end up-
turned as at 40 and provided with a minute jet opening 41 which is arranged below and
30 which discharges upwardly through the center of the mixing tube of each subsidiary burner. Said vapor supply pipe is also pro-
vided, on its upper side at its intersection with the vapor discharge ends 38 of the
35 pipes 33 with a jet opening 42 which is ar-
ranged below and discharges up through the mixing tube 21 of the main burner. The vapor supply pipe is provided with regulat-
ing valves 43 for the subsidiary burners. A
40 suitable air pressure gage 44 is provided preferably for the compressed air space of the oil supply tank 6.

A cylindrical chimney 45 is provided for each burner and is open at its upper end as
45 at 46 and provided with an annular base 47 providing a central opening 48 correspond-
ing in diameter with the exterior diameter of the burner base, so that the wall 24 of the burner base is adapted to extend up through
50 said opening and the said annular bottom 47 of the chimney is adapted to bear on and be supported by the band 30. Hence the chimneys are firmly supported by and centered on the burners and are prevented from casu-
55 ally toppling or becoming deranged and yet are adapted to be readily removed from the burners when this is desired. The base 47 of each chimney is provided with air intake openings 49. Each chimney is provided in
60 its front side with an opening 50 to afford access to the burner and with a hinged door 51 to close said opening.

The operation of my invention is as fol-
lows:—To start the stove a small quantity
of alcohol is placed in the generating cup 32
65 and ignited, thus heating the generating coils. The tank 6 having been supplied with oil and also supplied with compressed air, oil passes up through the pipes 33 and through the generating coils and is con-
70 verted in the coils into vapor and passes from the coils through the pipe 39 to the subsidiary burners. The vapor is dis-
charged into the mixing tube of each burner, through the openings 42 and 41 and in each
75 burner the mixture passes out through the hollow head into the space between the walls 23-24 and there burns so that an annular flame is maintained around each burner and in the base of its chimney. If it is not de-
sired to use the subsidiary burners the valves
80 43 may be closed. Or one subsidiary burner
only may be used in addition to the main burner, if desired but where only one burner is to be used this must be the main burner as
85 will be understood as the main burner is provided with the generating coils which supply not only itself but also the subsidiary burners.

Having thus described my invention, I 90
claim:—

1. In an oil stove a shelf, standard braces having their lower ends secured on the shelf, a band connecting the upper ends of the standard braces, a burner arranged in said band and having a wall extending upwardly therefrom, and a chimney having a base bearing on said band and provided with an opening through which the said wall extends so that the chimney is detachably secured 100 and is also centered on the burner.

2. In an oil stove a shelf, standard braces extending upwardly therefrom, oil supply pipes also extending up from the shelf, a generating cup arranged between and se-
cured to said oil supply pipes and standard braces, and a burner secured on the upper ends of the standard braces.

3. In an oil stove a shelf, standard braces extending upwardly therefrom, oil supply pipes also extending up from the shelf, a generating cup arranged between and se-
cured to said oil supply pipes and standard braces, and a burner secured on the upper ends of the standard braces, the said oil sup-
ply pipes having generating coils arranged in the said burner.

In testimony whereof I affix my signature in presence of two witnesses.

JNO. D. ROBERTSON.
